(No Model.)

G. W. JOHNSTON.

JAR.

No. 339,556.

Patented Apr. 6, 1886.

UNITED STATES PATENT OFFICE.

GEORGE WASHINGTON JOHNSTON, OF FLEMINGTON, NEW JERSEY.

JAR.

SPECIFICATION forming part of Letters Patent No. 339,556, dated April 6, 1886.

Application filed September 12, 1885. Serial No. 176,874. (No model.)

To all whom it may concern:

Be it known that I, GEORGE WASHINGTON JOHNSTON, a citizen of the United States, residing at Flemington, in the county of Hunterdon and State of New Jersey, have invented 5 certain new and useful Improvements in Jars, of which the following is a full, clear, and exact description.

This invention relates, primarily, to clay, 10 earthenware, or, as more commonly designated, stone jars or vessels having a stopper; and the invention consists in certain details of construction for facilitating the molding of the stopper of clay, and of applying sealing 15 mediums to the jar; and it also consists in means fixed to and accompanying the stopper for applying and removing the said stopper, all substantially as I will now proceed to particularly set forth and claim.

20 In the accompanying drawings, in the several figures of which like parts are similarly designated, Figure 1 is an elevation of the jar with its stopper removed. Fig. 2 is a vertical section of the jar sealed. Fig. 3 is a vertical 25 section of the stopper detached, with the stopper-operating device in position as a lever or wrench; and Fig. 4 is a section of the stopper at right angles to Figs. 2 and 3, with the gasket removed.

30 The jar or vessel *a* may be made in any approved manner, and has the internally-screw-threaded neck *b*, the upper edge, *c*, of which is convex or rounded to form a seat for the stopper *d*. This stopper is provided with the 35 cylindrical portion *e*, screw-threaded externally to match and engage the screw-thread of the neck *b* of the jar loosely, but still securely, and above the screw-thread on the cylindrical portion of the stopper is a groove, *f*, to receive

40 a rubber or other gasket, *g*, and above this groove the stopper has an annular flange, *h*, projecting outwardly sufficiently to extend over and cover the mouth of the neck of the jar, and on its under side, *j*, this flange is made 45 concave to match the convexity of the edge of the neck of the jar, the gasket *g* being interposed between said concave under side of the flange and the edge of the neck, so that when the stopper is in place in the neck of the jar 50 the jar will be sealed air-tight.

In order to overcome well-known difficulties in molding clay, in order to produce a good

and operative screw-stopper, I make my stopper with the hollow *k* and curve the bottom *l* upwardly. This construction enables the potter to produce an entirely practical stone screw-stopper, accurate in workmanship and true in its fit. 55

Horizontal holes *m* *m* are made at opposite points in the flange *h* of the stopper, to receive 60 a stopper-operating device, *n*, which in this instance is a piece of stiff wire having one end formed into a handle, *o*, and provided with a movable washer or other stop, *p*, arranged upon it on the inside of the flange, to prevent 65 the loss or accidental displacement of said operating device. This device *n* is of greater length than the external diameter of the flange, so as to have projecting ends upon each side of the stopper, whereby finger-holds are obtained 70 for use in operating (applying and removing) the stopper.

That portion of the operating device between the inside walls of the stopper and within the hollow *k* affords a handle for lifting 75 the jar, and thus is obviated the necessity for a jar-lifter or attached bails. The hollow *k* in this case affords a recess for the reception of the operator's fingers. When the jar (such as a preserve-jar) is of such size as that its stopper 80 may be grasped by one hand, the stopper may be applied and removed by the fingers engaging the projecting ends of the operating device; but when the jar is larger, as in snuff and mustard jars, the washer *p* may be moved 85 toward the opposite side of the stopper, (as in Fig. 3,) and the operating device *n* withdrawn from one hole, or pulled out of such hole sufficiently to afford a length adequate to grasp to employ said device as a lever in turning 90 the stopper.

The stopper-operating device is a fixture thereon, and hence no wrench nor other extraneous opener need be looked up when a jar is to be opened or closed. 95

As already stated, my invention is designed primarily for stone jars; but its principles are obviously equally applicable to jars and vessels of other materials.

What I claim is—

1. The stopper *d*, having the cylindrical externally-screw-threaded portion *e*, hollow *k*, arched bottom *l*, flange *h*, having its under side concave, and the gasket *g*, fitted in a 100

groove, f , in said stopper, combined with the vessel a , having an internally-screw-threaded neck and an edge to co-operate with the gasket and flange of the stopper, substantially as described.

5 2. The screw-stopper d , provided with the flange h , having the horizontal openings m , combined with a stopper-operating device, n , arranged in said holes and projecting beyond the stopper on either side to afford hand-holds for operating the stopper, and adapted to be partly withdrawn to serve as a lever, substantially as described.

10 3. The screw-stopper d , having the flange h , provided with horizontal openings m , combined with a stopper-operating device, n , arranged in said holes and projecting beyond the stopper on either side, and a washer or stop

on said device to limit its range of movement in said holes, substantially as described.

20 4. The screw-stopper d , provided with the hollow k and flange h , having the horizontal openings m , combined with the stopper-operating device n , permanently secured in the holes in said flange and projecting beyond said flange on either side, to afford hand-holds for applying and removing the stopper, and straddling and co-operating with the said hollow to form a bail or handle for said stopper, substantially as described.

25 In testimony whereof I have hereunto set my hand this 7th day of September, A. D. 1885.

GEORGE WASHINGTON JOHNSTON.
